UNITED STATES PATENT OFFICE.

SULLIVAN C. SWETT, OF WASHINGTON, DISTRICT OF COLUMBIA.

SHOW STAND OR CASE.

SPECIFICATION forming part of Letters Patent No. 379,139, dated March 6, 1888.

Application filed December 9, 1887. Serial No. 257,376. (No model.)

To all whom it may concern:

Be it known that I, SULLIVAN C. SWETT, a resident of Washington, in the District of Columbia, have invented certain new and useful 5 Improvements in Show Stands or Cases; and I do hereby declare the following to be a full, clear, and exact description of the invention, such as will enable others skilled in the art to which it pertains to make and use the same.

10 The object of my invention is to provide, for stores especially, a stand wherein boxes containing merchandise to be retailed may be compactly stored in such manner that one end of each shall be exposed; that the salesman, 15 without change of position, may have access to every box; that any number of boxes may be drawn out from the stand and opened at the same time and be independently supported and held firm when so withdrawn, and 20 that access to the contents of any box may be had only when the box is withdrawn—an advantage of importance to the average retailer of edible goods.

In the accompanying drawings, Figure 1 is 25 a perspective view of a stand embodying the invention. Fig. 2 is a central vertical section of the upper portion of the central standard-sleeve, showing the standard within.

In the drawings, A represents a horizontal 30 base mounted upon suitable rollers or casters, B, and C a vertical standard rigidly fixed therein.

D is a sleeve closed at its upper end and passed over the standard C. It is slightly 35 shorter than the free portion of the standard, upon the upper end of which it consequently rests, and which thus supports the weight of the sleeve and of all parts of the apparatus not thus far described. Shelf-supports, each 40 consisting of four arms, e e, at right angles with each other and in a plane perpendicular to the standard C, are rigidly mounted upon the sleeve D at intervals corresponding to and a little greater than the height of the boxes to 45 be supported. The corresponding arms of two consecutive shelf-supports are in vertical planes making an angle of forty-five degrees with each other, in order that when boxes with hinged covers are used any one may be opened 50 if slightly drawn radially outward from the standard without interfering with the next se-

ries of boxes above. It being premised that each of the arms, except in the upper set, supports precisely similar parts in the same way, one only need be considered. Upon each arm, 55 which is shown equal in width to the box to be supported, but which may be otherwise, a shelf, H, slides back and forth. A slot, I, dovetailed or broadest at the top, extends from end to end of the shelf parallel to its sides, and 60 in this slot fits a correspondingly beveled block, F, secured upon the arm. The block nearly equals the shelf in thickness and is long enough to prevent rotary motion of the latter.

The inward and outward movements of the 65 shelf are limited, respectively, by the bars M J, secured upon its outer and inner ends. The bar M projects above the shelf, to serve as a stop for the box placed thereon, and also below the shelf to meet the end of the arm E 70 when the shelf is at its innermost limit of motion. A third bar, G, is fixed to the upper surface of the shelf at a distance from the bar M somewhat greater than the width of the boxes to be used, and upon the outer edge of 75 this block is secured a curvilinear spring, R, between which and the bar M a box is held.

The construction is such that when a box, N, is placed in position, as shown, its inner side must press the spring inward before its 80 outer side can fall within the block M. It follows that the reaction of the spring presses the box firmly, preventing rattling and all accidental displacement, while at the same time the box may be instantly removed, if desired. 85 The shelves are conveniently operated by means of handles Q. When the boxes are provided with hinged covers, they cannot be opened while in the normal or innermost position on account of the overhanging box-supports above, but when partially drawn out the cover may be lifted, passing into the angular space between two adjacent boxes in the next set. When all the boxes are in their normal positions, their inner corners nearly meet, and 90 but slight vertical space is found between their tops and the lower surface of the arms above. The arms of the upper set are provided with marginal flanges O, and the flanges, which are lateral, extend as ribs across the upper surface 100 of the intervening arms and are continuous with corresponding flanges upon the diamet-

rically-opposed arms. The ribs thus inclose a rectangular surface and serve to retain a central box, P, while the projecting arms E' may support boxes similar to the box N. When all the boxes are in place, it is evident that the outer faces of those intended for merchandise are all exposed, while the box P, for wrappings, is practically concealed by those surrounding it.

10. What I claim is—

1. In a revolving stand for boxes, the combination, with a series of shelf-supporting arms arranged in sets at suitable intervals upon a rotating vertical support, of a series of shelves mounted upon said arms, respectively, by means adapted to permit limited independent motion to each, and provided with means for grasping and retaining a box placed thereon.

2. A revolving box-stand provided with sliding shelves adapted to be drawn out separately or at the same time, each of said shelves being provided with means for grasping and retaining with a firm pressure an ordinary box of proper size placed thereon.

25. 3. A revolving box stand provided with radially-sliding shelves arranged at suitable vertical intervals upon a vertical support, each shelf being in the vertical plane of the bisector of the angular interval between two shelves 30 next above itself.

4. A revolving box-stand consisting of a suitable base, a standard centrally fixed therein, a sleeve inclosing said standard and suspended from the top thereof, a series of horizontal arms arranged in sets at suitable intervals upon said sleeve, a series of shelves sliding longitudinally along said arms, respectively, and a series of spring-clutches attached, respectively, to each of said shelves and adapted to retain any suitable box placed 40 thereon.

5. The combination, with the revoluble vertical support of a box-stand, of the arms E, arranged thereon substantially as set forth, the slotted shelves H, engaging the beveled blocks 45 F, fixed upon said arms, the bars M and springs R, fixed to each of said shelves and adapted to engage any suitable boxes placed thereon, and the shelves E', provided with flanges O, all combined and co-operating substantially as 50 specified.

In testimony whereof I have signed this specification in the presence of two subscribing witnesses.

SULLIVAN C. SWETT.
